UNITED STATES PATENT OFFICE.

WILLIAM SILLMAN, OF NEW YORK, N. Y.

MACHINE FOR MAKING MILLBOARD.

No. 832,927.

Specification of Letters Patent.

Patented Oct. 9, 1906.

Application filed April 11, 1906. Serial No. 311,076.

To all whom it may concern:

Be it known that I, WILLIAM SILLMAN, a citizen of the United States of America, and a resident of the borough of Brooklyn, county 5 of Kings, city and State of New York, have invented certain new and useful Improvements in Machines for Making Millboard, of which the following is a specification.

My invention relates generally to the manufacture of plates, sheets, or boards out of pulp-like mixtures, and more specifically consists of improved mechanism for economically handling mixtures containing ingredients of great fineness of pulverization and 15 considerable specific gravity.

Heretofore it has been customary to employ apparatus of the general paper-making or cardboard-making machine type known in the art as "wet" machines for the purpose of making millboard and heavier plates or sheets out of various pulped fibrous materials, including short asbestos fibers mixed with various pulverized materials as fillers and as active constituents in the composition. 20 When a material which is finely pulverized, such as hydraulic cement, and which has considerable specific gravity, is employed in large quantity in such manufacture, the same is wasted in large part by being drawn 25 through the meshes of the wire-cloth-covered roll, upon which the pulp material is originally deposited by the action of suction and so carried away and also by being deposited in the bottom of the tank of the wet machine 30 by virtue of its greater specific gravity. My invention overcomes this feature of waste by practically compelling all of the heavier and finely-divided constituent of the mixture to enter into the finished product and has other 35 advantages and economies to be hereinafter pointed out.

One form of apparatus embodying my invention is illustrated in the accompanying two sheets of drawings, in which— 40 Figures 1, 1^a represent a side elevation and partial section of the machine, the section being taken on line 1 1 of Fig. 2; and Fig. 2 is a detail plan view of one mixing-box and connections and spreading-roller.

Throughout the drawings like reference-figures indicate like parts.

1 1 represent parts of the main frame of the machine, and 2 is an endless band of felt running over a series of guide-rollers 3 3, &c. 17 55 is a beater for cleaning said felt, 4 an adjusting-roll for guiding the felt in proper relation

to the beater, the position of which is controlled by the adjusting-lever 18.

23 23, &c., are suction-boxes of any convenient form, over which the felt 2 passes. 6c The suction may be produced by steam-jets, blowers, or in any convenient manner. (Not here illustrated.) The felt 2 is properly guided with reference to these suction-boxes by the adjustable roll 5, the position of which is controlled by the screw 21, operated by the hand-wheel shaft 22.

6 is a tightening-roll for the endless band of felt, the position of which is controlled by the screw 19 and the hand-wheel 20.

7 is a lower press-roll mounted in stationary journal-bearings 8, and 9 the upper press-roll, mounted in movable journal-bearings 10, carried by the lever 13, pivoted to the main frame at 14 and pulled downward by 75 the link 15, which is connected to the weighted pressure-lever 16.

11 is a screw for limiting the downward motion of the upper press-roll 9 by means of the adjustable hand-wheel nut 12. The endless felt of course passes between the press-rolls, as shown.

37 is the lower drying-roll for the felt, mounted in stationary journal-bearings 38, and 39 is the upper drying-roll, mounted in 85 journal-bearings 40 in the lever 42, pivoted to the main frame at 43 and pressed downward by the adjustable weight 44. Before entering these drying-rolls the felt is further cleansed by the water-spray 59.

24 is a mixing-box to which one portion of the stock or material, such as asbestos fiber beaten up with a sufficient quantity of water, is delivered through the stock-pipe 25.

26 is a water-pipe through which a suitable 95 quantity of water is delivered.

46 is a passage leading from the mixing-box to the distributing-trough 47. This passage is controlled by a gate 48. The trough 47 has a curved bottom, as shown in cross-section.

27 is an agitator of any convenient form located in the distributing-trough. As shown, it consists of a horizontal shaft with a series of beater-arms, the shaft being rotated 105 by a power-belt 41 or any other convenient means. The side of the distributing-trough which is next the agitator has a horizontal delivery-slot 28 formed therein at a height approximately corresponding to the axis of 110 the agitator 27. 29 is an adjustable gate for said slot.

30 is an inclined apron, of oil-cloth or similar material, extending from the edge of the distributing-trough, below the slot 28, down to a point over the upper strand of the endless felt 2. This apron has upturned sides 5 31 31.

32 is a regulating-roll having a face of rubber or similar suitable material, mounted in journal-bearings, which can be adjusted toward or away from the felt 2 by means of the adjusting-screw 33. This roll may coöperate with the felt 2 or with the apron 30 or with both at their juncture. It is rotated by the belt 34 in the direction to produce circumferential travel on its under side opposite to the travel of the felt at the point of contact therewith, or opposite to the direction of flow of the material down to the apron 30.

35 is an overflow-pipe from the mixing-tank, and 36 is a partition which permits any excess of material to flow over into the compartment 45, which serves as an overflow-box and which is drained by the overflow-pipe 35.

49 is a stock-chest, from which the fiber-pulp is drawn by any suitable means, as the pump 50, through pipe 51, and delivered to stock-pipe 25. The overflow-pipe 35 returns the surplus pulp to this stock-chest.

52 is a second distributing-trough to which the cement mixture is delivered by pipe 53, while additional water is supplied by pipe 54. An agitator 55 is located in this trough and rotated by any suitable means.

56 is a slot through which the diluted cement-solution flows down the apron 57 to the roll 32. The slot 56 is controlled by the gate 58.

The operation of my invention is as follows: 40 The guide-roller system and the endless band of felt 2 carried thereby being set in motion by means of power (not shown) and the supply of pulp-stock and water being turned on to the mixing-box the same will overflow on to the slot 28 in an even stream down through the slot 28 in an even stream down the inclined apron 30 to the upper strand of the endless felt 2, upon which it will be deposited in a thin even layer or film by means of the action of the regulating-roll 32 and the traveling motion of the felt. In the same way a thin sheet of film of dilute cement flows down the apron 57 onto roll 32 and is deposited on the previously-described pulp layer or film. A compound layer of cement and pulp is thus formed on the felt 2, and as this passes over the suction-boxes 23 45 50 55 and 28, a considerable quantity of the water or other liquid is sucked down through the felt and the layer of material on the felt is left in a sufficiently dry condition to adhere to the upper press-roll 9 as the felt passes through said press-rolls. This press-roll is usually made of iron. A film of material is therefore wound upon the upper press-roll 60 65 9, the same rising as the thickness of the

winding on its surface increases until a predetermined thickness is attained, when the cylindrical covering thus formed is slit longitudinally of the cylinder by a knife in the hands of the operator and removed in the shape of a plate or sheet whose width is the length of the cylinder and whose length is the circumference thereof. The felt, from which the major portion of the material has thus been removed, passes on down 70 75 around the guide-rolls 4 and up by the beater 17, which knocks out of the felt the small quantity of material remaining therein. The felt then passes between the drying-rolls 37 39, which squeeze the moisture out of it, and thence around the tightening-roll 6 back to the neighborhood of the mixing-tank, where it again has deposited upon it the film of material.

The advantages of my invention comprise 85 the practically complete saving of all waste of material, there being no opportunity for any of the cement or other substance to escape deposition upon the felt 2, the prolonged life of the felt itself, which is not forced into destructive contact with the wire-cloth roll used in former machines, the ease of regulation of the raw materials and machine and process at every point of operation, the possibility of 90 cleaning and drying the felt, &c.

It is evident of course that various changes could be made in the relative arrangement and form of the parts of my invention without departing from the spirit and scope thereof so long as the general principle of operation above set forth be adhered to.

Having therefore described my invention, I claim—

1. In a machine for making millboard and similar substances, the combination of a 105 pair of press-rolls, a series of suction-boxes, an endless band of felt passing over said suction-boxes and through said rolls and means for initially depositing the materials to be employed on the upper section of said endless felt.

2. In a machine for making millboard and similar substances, the combination of a pair of press-rolls, a series of suction-boxes, an endless band of felt passing over said suction-boxes and through said rolls and means for initially depositing the materials to be employed on the upper section of said endless felt, said means comprising a distributing-trough, a graduated sluiceway therein, approximating in length the width of the felt, and conveying means from said sluiceway to the upper section of the endless felt.

3. In a machine for making millboard and similar substances, the combination of a pair 125 of press-rolls, a series of suction-boxes, an endless band of felt passing over said suction-boxes and through said rolls and means for initially depositing the material to be employed on the upper section of said endless 130

- felt, said means comprising a distributing-trough, a graduated sluiceway therein, an agitator in the trough located adjacent to the sluiceway, and an apron extending from the sluiceway to a point over the upper section of the endless felt.
4. In a machine for making millboard and similar substances, the combination of a pair of press-rolls, a series of suction-boxes, an endless band of felt passing over said suction-boxes and through said rolls and means for initially depositing the material to be employed on the upper section of said endless felt, said means comprising a distributing-trough, a graduated sluiceway therein, an agitator in the trough located adjacent to the sluiceway, and an apron extending from the sluiceway to a point over the upper section of the endless felt, said apron having up-turned sides spaced apart a distance equal to the width of the web to be formed.
5. In a machine for making millboard and similar substances, the combination of a pair of press-rolls, a series of suction-boxes, an endless band of felt passing over said suction-boxes and through said rolls and means for initially depositing the materials to be employed on the upper section of said endless felt, together with a distributing-roll located over the felt near the point where the material is delivered to it.
6. In a machine for making millboard and similar substances, the combination of a pair of press-rolls, a series of suction-boxes, an endless band of felt passing over said suction-boxes and through said rolls and means for initially depositing the materials to be employed on the upper section of said endless felt, together with a distributing-roll located over the felt near the point where the material is delivered to it, said roll revolving in a direction to produce circumferential travel on its under side opposite to the travel of the felt at the point of contact therewith.
7. In a machine for making millboard and similar substances, the combination of a pair of press-rolls, a series of guide-rolls, an endless band of felt passing around said guide-rolls and through said press-rolls, means for initially depositing the materials to be employed on the upper section of said endless felt, and means disposed between the point of such deposit and the press-rolls for removing surplus water from the materials.
8. In a machine for making millboard and similar substances, the combination of a pair of press-rolls, a series of guide-rolls, an endless band of felt passing over said guide-rolls and through said press-rolls, and means for initially depositing the materials to be employed on the upper section of said endless felt, said means comprising a distributing-trough, a graduated sluiceway therein, approximating in length the width of the felt, and conveying means extending from said sluiceway to the upper section of the endless felt.
9. In a machine for making millboard and similar substances, the combination of a pair of press-rolls, a series of guide-rolls, an endless band of felt passing over said guide-rolls and through said press-rolls, and means for initially depositing the materials to be employed on the upper section of said endless felt, together with a distributing-roll located over the felt near the point where the material is delivered to it.
10. In a machine for making millboard and similar substances, the combination of a pair of press-rolls, a series of guide-rolls, an endless band of felt passing over said guide-rolls and through said press-rolls and means for initially depositing the materials to be employed on the upper section of said endless felt, together with a distributing-roll located over the felt near the point where the material is delivered to it, said roll revolving in a direction to produce circumferential travel on its under side opposite to the travel of the felt at the point of contact therewith.
11. In a machine for making millboard and similar substances, the combination of a pair of press-rolls, a series of guide-rolls, an endless band of felt passing around said guide-rolls and between said press-rolls, means for initially depositing a film of pulped fiber on said endless felt and separate means for depositing a solution of cement on said endless felt.
12. In a machine for making millboard and similar substances, the combination of a pair of press-rolls, a series of guide-rolls, an endless band of felt passing around said guide-rolls and between said press-rolls, means for depositing a film of pulped fiber on said endless felt and separate means for initially depositing a solution of cement on said endless felt, together with means disposed between the point of such deposit and the press-rolls for removing surplus water from the materials on the felt.
13. In a machine for making millboard and similar substances, the combination of a pair of press-rolls, a series of guide-rolls, an endless band of felt passing around said guide-rolls and between said press-rolls, a distributing-trough for fibrous pulp having a graduated sluiceway therein, approximately as long as the felt is wide, an apron extending downward from said sluiceway to said felt, a distributing-tank for a cement solution having in a similar sluiceway therein, and a second apron extending downward from said last-mentioned sluiceway to a point over the lower end of the first-mentioned apron.
14. In a machine for making millboard and similar substances, the combination of a pair of press-rolls, a series of guide-rolls, an endless band of felt passing around said guide-rolls and between said press-rolls, a distrib-

4
 5. A distributing-trough for fibrous pulp having a graduated sluiceway therein, approximately as long as the felt is wide, an apron extending downward from said sluiceway to said felt, a distributing-tank for a cement solution having a similar sluiceway therein, and a second apron extending downward from said last-mentioned sluiceway to a point over the lower end of the first-mentioned apron together with a distributing-roll upon which one apron discharges while the other discharges under said rolls.

10. 15. In a machine for making millboard and similar substances, the combination of a pair of press-rolls, a series of guide-rolls, an endless band of felt passing around said guide-rolls and between said press-rolls, a distributing-trough for fibrous pulp having a graduated sluiceway therein, approximately as 15 long as the felt is wide, an apron extending downward from said sluiceway to said felt, a distributing-tank for a cement solution having a similar sluiceway therein, and a second

20. 25. apron extending downward from said last-mentioned sluiceway to a point over the lower end of the first-mentioned apron, together with a distributing-roll upon which one apron discharges while the other discharges under said roll, and a series of suction-boxes located between the distributing-roll and the press-rolls and over which the felt passes.

30. 35. 16. The combination of the mixing-box, the distributing-trough, the submerged passage-way between them, the overflow-box beside the mixing-box, the stock-chest, a pump and connections for drawing the stock from the stock-chest and discharging it into the mixing-box, and an overflow-pipe leading from the overflow-box to the stock-chest. 40

Signed at Brooklyn, New York, this 3d day of April, 1906.

WILLIAM SILLMAN.
